UNITED STATES PATENT OFFICE.

ADOLPH M. HOLSTEIN, OF SYRACUSE, NEW YORK.

DESIGN FOR A PANEL ORNAMENT FOR FURNITURE AND CASKETS AND FOR INTERIOR AND EXTERIOR DECORATIONS.

52,656.

Specification for Design.

Patented Nov. 12, 1918.

Application filed August 22, 1917. Serial No. 187,566. Term of patent 3½ years.

To all whom it may concern:

Be it known that I, ADOLPH M. HOLSTEIN, a citizen of the United States, residing at Syracuse, in the county of Onondaga and State of New York, have invented a new, original, and ornamental Design for a Panel Ornament for Furniture and Caskets and for Interior and Exterior Decorations, as set forth in the annexed specification.

The drawing is an elevation or face view of this design.

I claim:

The ornamental design for a panel ornament for furniture, and caskets and for interior and exterior decorations, substantially as shown.

In testimony whereof, I have hereunto signed my name, at Syracuse, in the county of Onondaga, and State of New York, this 30th day of July, 1917.

ADOLPH M. HOLSTEIN.
